UNITED STATES PATENT OFFICE.

RALPH BERTRAM DEEMS, OF WICHITA FALLS, TEXAS, ASSIGNOR OF ONE-HALF TO
JOHN D. COYLE, OF WICHITA FALLS, TEXAS.

SMOKELESS AND ODORLESS OIL BURNER.

Application filed December 4, 1923. Serial No. 678,529.

To all whom it may concern:

Be it known that RALPH BERTRAM DEEMS, a citizen of the United States, residing at Wichita Falls, in the county of Wichita 5 and State of Texas, has invented certain new and useful Improvements in Smokeless and Odorless Oil Burners, of which the following is a specification.

The present invention relates to a burner 10 using oil as fuel and the main object of the invention is to construct a smokeless and odorless burner which can be used not only for domestic heating plants but for portable as well as stationary boilers. This burner 15 is so constructed that it creates its own pressure and intermingles the oil which is vaporized in the burner with a sufficient amount of air and steam.

The burner may be built in different sizes 20 so that, for instance, for small plants a single unit is installed while for larger furnaces or for boilers the burner is preferably made in sections. This facilitates the assembling of the burner under the boiler as 25 the complete burner extends the entire length of the boiler and in that case consists of end and intermediary sections properly united with steamtight joints.

In the accompanying drawings, one embodiment of the invention is illustrated, and—

Figure 1 is a perspective view of the burner assembled;

Figure 2 is a section along line 2—2 of 25 Figure 3 with some parts broken off;

Figure 3 is a vertical section along line 3—3 of Figure 2;

Figure 4 is a vertical section along line 4—4 of Figure 2;

Figure 5 is a plan view similar to Figure 2 of a burner intended for a small furnace, and

Figure 6 is a diagrammatic plan view of the burner as applied to a reclining boiler.

In the drawings, reference numeral 10 represents the base of the burner and reference numeral 11 the top or fuel mixing portion. As already described, the burner is preferably made in sections so that the base 50 portion 10 consists of two semi-circular sections 12 and 13 which are united by bolts 14 connecting the radially projecting flanges 15 between which suitable packing 16 is inserted. As best illustrated in Figure 3 55 the base portion has an annular channel 17

of triangular cross section with a perpendicular wall 18 at the inner periphery thereof and a slanting wall 19 running downwardly and outwardly to unite with the bottom wall 20. Around the lower outer corner of this channel is provided an upstanding flange 21 which extends a considerable distance above the top of the channels 17. In the slanting wall 19 there is provided a series of fuel apertures 22 arranged in 60 a circle around the burner as seen in Figures 1 and 2. These apertures run at right angles to the inclined wall 19 so that the axes of said apertures strike the upstanding flange 21 about midway between its top and bottom. Below this row of apertures and between the inclined wall 19 and the flange 21 is formed a pocket 23 which constitutes the ignition trough, see 65 Figure 3.

The top or fuel mixing portion 11 is preferably constructed in the same manner as the base portion, that is to say, in two sections 24 and 25 which are bolted together as at 70 26 with their inwardly and outwardly directed radial flanges 27 between which a suitable packing 28 is inserted to make the joints steam tight. This top portion has two annular channels 29 and 30 arranged 75 one above the other, of which the top channel 29 constitutes a steam chamber, while the lower channel 30 constitutes an oil vapor chamber. As illustrated in the drawings these chambers are of square cross section, but it is evident that any other cross section 80 may be used depending on conditions. Midway between the two ends of the section 24 is provided a boss 31 and from this boss extends inwardly a transom 32 across the channel or steam chamber 29 and a similar 85 transom 33 extends across the lower channel or oil vapor chamber 30. These two transoms are offset with regard to each other, see Figure 4, so that, for instance, the transom 32 is situated to the left of the central vertical plane running through the boss 31, while the transom 33 in the oil vapor chamber 30 is positioned to the right of the same plane.

In the boss 31 and communicating with 90 the end of the vapor chamber 29 to the left of the transom 32 is provided a port 34 with which a water supply pipe 35 is connected. In this port is inserted a needle valve 36 for regulating the inlet opening of said 95 100 105 110

- port into the steam chamber 29. Similarly, a port 37 leads in through the boss 31 into the oil vapor chamber 30, but this port is situated to the right of the transom 33 at 5 the adjacent end of the chamber. An oil pipe 38 is connected to the port 30 and also provided with a needle valve 39 for regulating the amount of oil supplied through the port 37 to the oil vapor chamber 30.
- 10 Directly on said central vertical plane running through the boss 31 is furnished a nozzle 40 extending inwardly in radial direction from the steam chamber 29 and directly below this nozzle a second nozzle also 15 pointing downwardly opens from the oil vapor chamber 30 in radial direction therefrom. The openings of said two nozzles are preferably offset in radial direction to each other so that the steam nozzle 40 extends 20 farther in than the oil vapor nozzle 41 as best seen in Figure 3. In axial alignment with each of said nozzles are shown drilled and plugged openings 55 and 56 partly for facilitating the assembling and partly for 25 cleaning the nozzles.
- Around these two nozzles is formed a mixing chamber 42 on the inner side of the section 24 of the top portion of the burner and a pipe 43 is preferably threaded on the 30 under side to communicate with this mixing chamber. Similarly, another pipe 44 is threaded into a knee 45 formed on the inner side of the section 12 of the base portion of the burner and the two pipes 43 and 44 are 35 preferably connected by a union 46. Through the knee 45 an inlet is provided to the annular channel 17 in the lower section.
- As best seen in Figures 1 and 3, the top portion 11 of the burner is supported by 40 means of legs 48 upon the flange 24 of the base portion thereof. These legs are, as indicated in Figure 3, cast in one with the corresponding upper sections 24 and 25 and have fingers 49 engaging with the flange 21.
- 45 It is evident that in some cases it might be preferable to make these legs separate castings and secure them in suitable manner both to the top and bottom portions of the burner.
- 50 In Figure 5 is shown a simplified form of the burner which is preferably made for small heating plants in which the top portion 50 and the base portion 51 together with the spacing legs are all cast in one, 55 otherwise the construction is similar to that already described.
- When the device is to be used for large 60 boilers whether stationary or portable the burner must naturally have a length corresponding to that of the boiler so that all parts thereof will be heated simultaneously. In that case the sections 12 and 24 will be placed under the forward end of the boiler nearest the door and the sections 13 and 25 placed at the other end thereof. Between 65 these two ends, straight tubular sections 52 are inserted according to the length of the boiler and firmly united with the flanges 15 and 27 of the end sections. This is best shown in Figure 6 where the arrangement 70 is diagrammatically illustrated with the semi-circular sections 12 and 24 at one end and the semi-circular sections 13 and 25 at the opposite end representing the length of the boiler while the straight tubular sections 52 each provided with a steam chamber and a fuel vapor chamber are inserted between the flanges of the end sections and firmly united therewith. To start the burner, the needle valve 39 is first opened to admit oil 75 to the chamber 30. As the port 37 of the needle valve 39 is situated at the opposite end of the chamber to the nozzle 41, the oil will have to pass all around the chamber until it reaches the nozzle 41 when it will run through the same and down the pipes 43 and 44 and through the apertures 22 into the pocket 23 where a certain amount thereof 80 will collect. This oil is then ignited in the ordinary manner and after having burned 85 for a short while will start to vaporize the oil in the channel 17 first and later the oil in the chamber 30. As soon as the upper sections have been sufficiently heated, the needle valve 40 is also opened admitting 90 water which will circulate from one end to the other of the chamber 29. It should here be noted that on account of the offset 95 of the transoms 32 and 33 and the positioning 100 of the needle valves and ports at the opposite ends of the steam and fuel vapor chambers, the steam will circulate in clockwise direction as indicated by arrows X in 105 the different views, while the oil vapors will circulate in the opposite or counter-clockwise direction as indicated by arrows Y. The water will then be vaporized so that the 110 steam jet is driven downwardly from the nozzle 40 meeting an oil vapor jet from the chamber 30 ejected through the nozzle 41 in the mixing chamber 42 and, on their way downwards through the pipes 43 and 44, these jets will closely intermingle and pass out through the apertures 22 where the fuel 115 will be immediately ignited by the flames in the combustion chamber 23. By properly adjusting the two needle valves 36 and 39, the proper fuel mixture is obtained and it 120 is evident that after the oil that first collected in the pocket 23 has been consumed no smoke whatsoever will be formed as the combustion is complete; nor will there be any odors. When the burner has been 125 properly adjusted and is running normally, pressure is automatically created in the steam and oil chambers to feed the burner in the proper manner.
- By directing the fuel jets against the heated flange 21 in the ignition trough 23, a 130 greatly increased vaporization and fine dis-

tribution of the fuel is maintained. This flange also tends to direct the resulting intensive heat against the upper sections 24 and 25,

5 In manufacturing the burner for the market due consideration must naturally be paid to its installation in different kinds of plants and the burner will as a consequence be built in different sizes and made in single 10 units or built up of several different sections and the applicant reserves the right of making any modifications for this purpose within the scope of the claims, such modifications might, for instance, consist in making 15 the nozzles 40 and 41 separate instead of casting them integral with the upper sections; in some instances it might also be advisable to place the annular chambers 29 and 30 side by side instead of one above the 20 other.

The relative proportions are about what has been shown in the drawings so that, for instance, the sectional area of the parts 43 and 44 is about the sectional area of each of 25 the chambers 29 and 30 and also the same as the sectional area of the channel 17. In this manner the forcing out of the fuel through the apertures 22 will be greatly increased and the pressure in the mixing 30 chamber 42 which is obtained by the action of the burner itself will always be sufficient to drive the fuel into the ignition trough formed by the pocket 23, where the fuel mixture is brought into an exceedingly fine 35 state of vaporization by being thrown violently against the heated flange or baffle 21.

Having thus described the invention, what is claimed as new is:

1. In a liquid fuel burner, upper and 40 lower members one superimposed with relation to the other and each provided with channels; one of the channels in the upper member constituting a steam chamber and an adjacent channel therein constituting a 45 liquid fuel vapor chamber, the opposite ends of said chambers having suitable valved connection with water and fuel supplies respectively and the other ends of the chambers both opening into a mixing chamber formed 50 in the upper member; one of the channels in the said lower member constituting a distributing chamber and the adjacent channel therein an ignition trough and suitable conduits connecting said mixing chamber with 55 said distributing chamber, apertures being provided for passing fuel mixture from said distributing chamber to said ignition trough.

2. In a liquid fuel burner, upper and 60 lower annular members one superimposed with relation to the other and each provided with annular channels; one of the channels in the upper member constituting a steam chamber and an adjacent channel therein constituting a liquid fuel vapor chamber, the 65 opposite ends of said chambers having suit-

able valved connection with water and fuel supplies respectively and the other ends of the chambers both opening into a mixing chamber formed in the upper member; one of the channels in the said lower member 70 constituting a distributing chamber and the adjacent channel therein an ignition trough and suitable conduits connecting said mixing chamber with said distributing chamber, apertures being provided for passing fuel 75 mixture from said distributing chamber to said ignition trough.

3. In a liquid fuel burner, upper and lower annular members one superimposed with relation to the other and each provided with annular channels; one of the channels in the upper member constituting a steam chamber and an adjacent channel therein 80 constituting a liquid fuel vapor chamber, the opposite ends of said chambers having suitable valved connection with water and fuel supplies respectively and the other ends of the chambers both opening into a mixing chamber formed in the upper member; one of the channels in the said lower member 85 constituting a distributing chamber and the adjacent channel therein an ignition trough and suitable conduits connecting said mixing chamber with said distributing chamber, apertures being provided for passing fuel mixture from said distributing chamber to said ignition trough; said ignition trough surrounding said distributing chamber and having an outer annular flange against which the fuel mixture is directed by said apertures.

4. In a liquid fuel burner, upper and lower annular members one superimposed with relation to the other and each provided with annular channels, each of said members being made in sections; one of the channels in the upper member constituting a steam chamber and an adjacent channel therein 100 constituting a liquid fuel vapor chamber, the opposite ends of said chambers having suitable valved connection with water and fuel supplies respectively and the other ends of the chambers both opening into a mixing chamber formed in the upper member; one of the channels in the said lower member 105 constituting a distributing chamber and the adjacent channel therein an ignition trough and suitable conduits connecting said mixing chamber with said distributing chamber, apertures being provided for passing fuel mixture from said distributing chamber to said ignition trough.

5. In a liquid fuel burner, upper and lower annular members one superimposed with relation to the other and each provided with annular channels, each of said members being made in sections; one of the channels in the upper member constituting a steam chamber and an adjacent channel 110 therein constituting a liquid fuel vapor 115 chamber.

4
chamber, the opposite ends of said chambers having suitable valved connection with water and fuel supplies respectively and the other ends of the chambers both opening 5 into a mixing chamber formed in the upper member; one of the channels in the said lower member constituting a distributing chamber and the adjacent channel therein an ignition trough and suitable conduits 10 connecting said mixing chamber with said distributing chamber, apertures being provided for passing fuel mixture from said distributing chamber to said ignition trough; said ignition trough surrounding said distributing chamber and having an outer annular flange against which the fuel mixture 15 is directed by said apertures.

6. In a liquid fuel burner, upper and lower annular members one superimposed 20 with relation to the other and each provided with annular channels, each of said members being made in sections; one of the channels in the upper member constituting a steam chamber and an adjacent channel

therein constituting a liquid fuel vapor chamber, the opposite ends of said chambers having suitable valved connection with water and fuel supplies respectively and the other ends of the chambers both opening into 25 a mixing chamber formed in the upper member; one of the channels in said lower member constituting a distributing chamber and the adjacent channel therein an ignition trough and suitable conduits connecting said mixing chamber with said distributing chamber, apertures being provided for passing fuel mixture from said distributing chamber to said ignition trough; said ignition trough surrounding said distributing chamber and having an outer annular flange 30 against which the fuel mixture is directed 35 by said apertures; said members being spaced apart and uprights adapted to support the upper member on the lower member. 40

In testimony whereof I affix my signature. 45

RALPH BERTRAM DEEMS. [L.S.]
